[57] CLAIM

The ornamental design for a wire fence tightener, as shown and described.

DESCRIPTION

FIG. 1 is a top perspective view of a wire fence tightener showing my new design;

FIG. 2 is a top plan view thereof;

FIG. 3 is a bottom plan view thereof;

FIG. 4 is a front elevation view thereof, the rear elevation view being identical with the exception of the central wire section not shown; and,

FIG. 5 is a left side elevation view thereof, the right side elevation view being a mirror image.

FIG. 1.

FIG. 2.

FIG. 3.

FIG. 4.

FIG. 5.
